UNITED STATES PATENT OFFICE

SAMUEL MARCUS, OF BROOKLYN, NEW YORK, ASSIGNOR TO MARKON MANUFACTURING CO., INC., OF NEW YORK, N. Y., A CORPORATION OF NEW YORK

TONGUE AND TEETH SET FOR DOLLS AND THE LIKE

Application filed October 4, 1927. Serial No. 223,942.

This invention relates to a tongue and teeth set for dolls and the like, and an object of the invention is to provide a set which may be easily and cheaply manufactured and which 5 may be readily attached in position within the mouth opening of a doll head.

A more detailed object is to provide a set which may be made of sheet metal or other appropriate sheet material and embodying 10 attaching means by which the set may be attached within the doll head.

A further object is to provide a set comprising improved means whereby the teeth member or members thereof are retained or 15 formed.

A more specific object is to provide a set in which the teeth member is formed separately from the remainder of the structure and in which clamp means is provided for 20 retaining the teeth member connected in position as a part of the structure.

A further specific object is to provide a set in which the teeth member may be formed as 25 an integral part of the structure.

Other objects and aims of the invention, more or less specific than those referred to above, will be in part obvious and in part 30 pointed out in the course of the following description of the elements, combinations, arrangements of parts and applications of principles constituting the invention; and the scope of protection contemplated will be indicated in the appended claims.

In the accompanying drawings which are 35 to be taken as a part of this specification, and in which I have shown merely a preferred form of embodiment of the invention:

Fig. 1 is a side elevational view of a tongue and teeth set constructed in accordance with 40 this invention and showing the same as it appears in position within a doll head, a portion of the doll head being shown in vertical section.

Fig. 2 is a horizontal sectional view 45 taken substantially upon the plane of line II-II of Fig. 1.

Fig. 3 is a front elevational view of the tongue and teeth set appearing in Fig. 1, the 50 relative position of the mouth opening of the doll head being shown by heavy dotted lines.

Fig. 4 is a vertical sectional view taken substantially upon the plane of line IV-IV of Fig. 3.

Fig. 5 is a view similar to Fig. 4 but illustrating a modification in which more than one 55 teeth member is present.

Fig. 6 is a view similar to Fig. 3 but illustrating a modification as to the manner of providing the teeth.

Fig. 7 is a side elevational view of the 60 structure seen in Fig. 6, a part being shown in vertical section substantially upon the plane of line VII-VII of Fig. 6, and.

Figs. 8 and 9 are views similar to Figs. 6 and 7 but illustrating a further modification 65 of the manner of providing the teeth.

Referring to the drawings for describing in detail the structures illustrated therein, and referring specifically first to the structure illustrated in Figs. 1 to 4, the reference 70 character L indicates a part of the front portion of a doll head, the mouth opening being shown at 1.

The tongue and teeth set with which this 75 invention is concerned is indicated generally by the reference character G, said set comprising broadly a base or mouth representing portion as 2, a tongue representing portion 3 centrally of the base 2, and a teeth representing portion 4, all held together as a single 80 entity and adapted to be inserted into and fastened in position within the mouth opening 1 of the head in approximately the relation as clearly indicated in Figs. 1 to 3 of the drawing.

In the structure as disclosed in Figs. 1 to 4 the teeth portion 4 is formed as a separate piece of material, such as sheet metal, celluloid, or otherwise suitably colored and shaped to represent human teeth, the remainder of 90 the structure being likewise formed of suitable material either sheet metal, celluloid, or otherwise, and having an extending portion as 5 bent over upon itself as at 6 to provide a clamp within which the teeth member is gripped and held in appropriate relation to the tongue 3.

The material from which the base and tongue portions are formed would of course be colored, at least upon its outwardly facing 100

surface, to represent the tongue and mouth of an infant, for instance a reddish color.

The base or mouth portion 2 is cupped in simulation of the hollow interior of the mouth of a small infant, the tongue 3 being pressed outwardly at the centre of the mouth portion in a suitably characteristic shape and disposition.

The size of the structure is such that when viewed through the mouth opening 1 of the doll head only the tongue 3, the lower margin of the teeth member 4, and the central part of the base 2 will be visible, as will be apparent from an inspection of Fig. 3 wherein the dotted line 7 represents the relative size and position of the mouth opening.

When the set is placed within the doll head the extension part 5 thereof may rest against an interior surface part as 8 of the head above the mouth opening while a lower marginally projecting part as 9 may rest against an interior surface as 10 of the head below the mouth opening. The opposite end marginal parts as 11 and 12 may rest against adjacent interior surface parts as 13 and 14 respectively. The position of the set with respect to the mouth opening may thus be positively defined, and when the set has been once thus positioned, or as nearly thereto as is practicable considering the surface contour of the head, then the set is attached rigidly in that position.

The operation of attaching the set may be effected in any appropriate manner either by the use of cement, separate or integral fastening devices, or otherwise. In the instance illustrated however integral fastening devices are employed. These consist of a pair of tangs as 15 and 16 continuing as integral extensions from the opposite ends of the base 2. At the time when the set is being inserted into position within the head these tangs extend normally backwardly beyond the plane of the surfaces 13 and 14, as indicated by the dotted lines in Fig. 2, so as not to interfere with the bringing of said surfaces into engagement with the opposing parts of the doll head. They however are bendable and are intended to be bent forwardly to drive the pointed ends of the tangs into the material of the head after the final desired position of the set has been reached, as indicated by the full lines in Fig. 2.

Any appropriate tool or other device may be employed for carrying the set into the head and for bending the tangs to effect attachment of the set, such for instance as the tool shown and described in the application Serial No. 223,941, filed October 4th, 1927, which is being filed concurrently herewith.

In Fig. 5 is shown a modification in which more than one teeth member is present. In this instance the lower marginal edge of the base 2 is provided with an extension as 17

which is turned over upon itself as at 18 to provide a clamp within which is received and held the second teeth member as 19, all in the same manner as heretofore described with respect to the manner of forming and supporting the teeth member 4.

In this same manner any number of teeth members may be employed, and likewise their position with respect to the tongue 3 may vary in accordance with the artistic dictates of the designer or manufacturer since obviously the extensions 5—17 may be placed at substantially any selected locality about the margin of the base 2, and likewise the teeth members may be of any form either representing a single tooth, a plurality of uniform teeth, a plurality of teeth of uneven or grotesque appearance, or otherwise.

In the modification Figs. 6 and 7 a structure is proposed in which the teeth forming portion is integral with the remainder of the structure. In this instance the teeth forming portion consists merely of a turned over extension as 20 of a marginal part of the base. This turned over extension may be provided at any selected point about the margin of the base, either above or below the tongue 3, and it may be given any desired shape according to the artistic dictates of the designer so that, as in the previous structure, any form or number of teeth may be represented and in any selected relation to the mouth opening.

It will be understood of course that the base and tongue portions should be properly colored for instance reddish color as in the previous structure while the teeth should be of appropriate teeth color. Such coloring may be applied or effected in any appropriate manner either before or after the shaping of the sheet material into set form, but it is herein suggested that as an inexpensive and satisfactory manner of producing the desired result the piece of sheet material from which the set is to be formed shall be previously coated with an appropriate reddish coloring material as 22 on one surface and an appropriate whitish coloring material as 23 on the opposite surface so that when the set is completed the turning in of the extension 20 will expose the whitish color upon the outer surface of the teeth portion, as clearly shown in the sectional portion of the illustration Fig. 7.

In Figs. 8 and 9 is suggested a further modified manner in which the set may be economically produced. In this instance it is proposed that the blank from which the set is to be formed shall be lithographed on one surface in such manner that when the set is formed a portion of the set of suitable whitish color shall be raised and suitably formed upon the base 2 so as to represent the teeth, as at 21, in said Figs. 8 and 9.

In other respects the structures Figs. 6 to

9 correspond with the arrangement and manner of use as described with respect to the structures Figs. 1 to 5, and obviously the raised tooth forming portion 21 of the structure Figs. 8 and 9 may be produced at any 5 selected locality upon the base and may be of any form etc. to satisfy the desires of the manufacturer for artistic results, novelty or grotesqueness, as in the other structures.

10 Although it is a feature of the present invention to provide means as hereinabove referred to for representing teeth as parts of the set, it will nevertheless be understood that in some instances the mouth and tongue 15 portions may be employed, the teeth being wholly omitted and on this account it is desired to mention that the term "tongue and teeth set" as herein used is merely a commercial term generally employed with reference 20 to sets of this type, and that said term is herein intended to comprehend any form of device arranged within the mouth or similar opening of the doll head where teeth are actually present as a part of the structure or not.

25 As many changes could be made in this construction without departing from the scope of the invention as defined in the following claims, it is intended that all matter contained in the above description, or shown 30 in the accompanying drawings, shall be interpreted as illustrative only and not in a limiting sense.

Having thus described my invention, what I claim as new and desire to secure by Letters 35 Patent is:—

1. A tongue and teeth set for doll heads, said set comprising a base part having a tongue portion projecting therefrom, a separately formed teeth member, and clamp 40 means comprised in the structure for gripping and frictionally retaining the teeth member connected in position.

2. A tongue and teeth set for doll heads, said set comprising a base part having a tongue portion projecting therefrom, a separately formed teeth member, and an extension continuing from the base member bent over upon itself to provide a clamp within 45 which the teeth member is held.

50 3. A tongue and teeth set for doll heads, said set comprising a tongue member, a separately formed teeth member, and an extension continuing from one of said members bent over upon itself to provide a clamp within 55 which the other member is gripped to hold said members assembled.

4. As an attachment for doll heads, a tongue and teeth member, the tongue member being formed of sheet material having its 50 central portion pressed forwardly to represent a tongue, the portion of said sheet material at the base of the tongue continuing outwardly therefrom and thence forwardly into a general cup shape to represent the interior 60 of a mouth containing the tongue, the teeth

member formed separately from the tongue member, and an integral part of said sheet material continuing from the margin thereof being bent to constitute holding means for the teeth member.

5. An attachment for a doll head having a mouth opening, said attachment comprising a tongue member having a portion shaped to represent a human tongue intended to be positioned within the mouth opening of the doll head, said member having other portions disposed to engage against parts of the head adjacent the mouth opening co-operative with said parts to define the position of the tongue with respect to the mouth opening 70 preparatory to fastening the member within the head, and fastening means for said member comprising bendable tangs formed integral with said member bendable into impaled relation within the material of the head 75 said tangs being disposed with respect to the remainder of said member so as to stand out of engagement with the head during the preliminary engagement of the last mentioned portions of the member against the head. 80

In testimony whereof I affix my signature. 85
SAMUEL MARCUS.
